UNITED STATES PATENT OFFICE.

JOHN WM. DAVIES, OF BARNESBORO, PENNSYLVANIA.

WRENCH.

1,379,536.

Specification of Letters Patent.

Patented May 24, 1921.

Application filed May 25, 1920. Serial No. 384,088.

To all whom it may concern:

Be it known that I, JOHN W. DAVIES, a citizen of the United States, residing at Barnesboro, in the county of Cambria and State of Pennsylvania, have invented certain new and useful Improvements in Wrenches, of which the following is a specification, reference being had therein to the accompanying drawings.

10 This invention relates to an improvement in automatic wrenches, and has for its object the construction of a simple and efficient wrench that can be quickly adjusted to accommodate different size nuts, and which 15 can also be adjusted to make the operation on the nuts easier, by reason of positioning the shank or handle of the wrench at an angle to the head, carrying the jaws.

With this and other objects in view, my 20 invention comprises certain novel combinations, constructions and arrangements of parts as will be hereinafter described, illustrated in the accompanying drawings, and more particularly pointed out in the appended claims.

In the drawings:

Figure 1 is a view in side elevation of a wrench constructed in accordance with the present invention, while

25 Fig. 2 is a vertical central section of the same.

Fig. 3 is a perspective view of the movable screw-carrying casing.

Fig. 4 is a fragmentary view in elevation, 30 showing the inner end of the shank and the inner end of the head, pivotally mounted on the shank.

Referring to the drawings by numerals, 1 designates the shank which is provided with a grip 2, and the inner end is bifurcated as at 3. An axle 4 is screwed into the bifurcated portion 3 of the handle, and pivotally mounted on the axle 4 is a head 5. The inner end of the head 5 is provided with notches 6, into which notches a dog 7 extends; the dog 7 is carried by the locking plunger 8. Secured to the outer end of the plunger 8 is a ball-grip 9. In a pocket 10, formed in the shank 1, is a coil spring 11; this spring 11 is placed around the plunger 8 and bears at one end against the dog 7 for holding the dog in one of the notches 6 of the head 5, whereby the head will be retained in an adjusted position upon the axle 4, but upon the operator pulling outwardly upon the ball-grip 9, the dog will

be removed from the particular notch 6 in which it is seated, freeing the head and allowing the head to be swung to the desired position upon the axle 4.

On the outer end of the head 5 is formed an integral primary jaw 12, and in the body of the head is a large opening 13, in which the movable screw-carrying casing 14 is slidably mounted.

A slideable, auxiliary jaw 15 is provided with an integral neck 16, which neck has a groove 17 formed in one side, and a rib 18, integral with the head 5, extends into the groove 17. Teeth 19 are formed on the lower edge of the neck 16, and the screw 20, rotatably mounted at its ends in apertures 21, on the ends 22 of the casing 14, meshes with the teeth 19, whereby the neck 16 and jaw 15 can be adjusted upon the head 5, by the rotation of the screw 20; the meshing of the screw with the teeth 19 results in a positive adjustment of the jaw 15 when the screw is rotated.

The ends 22 of the casing 14 are integral with the bottom 23 of the casing, and depending from opposite edges of the bottom 23 are flanges 24; these flanges 24 bear upon the sides of the head 5. Under the bottom 23 is a coil spring 25, which is seated in a socket 26 formed in the head. The spring 25 normally keeps the screw 20 meshing with the teeth 19, but upon the operator pulling down upon the casing 14, the screw 20 will be disengaged from teeth 19, permitting adjustment of the jaw 15 with respect to the jaw 12 upon the head 5. The ends 22 of the casing 14 are bifurcated, at 26 and 27; these bifurcated portions straddle the neck 16; the flanges 24 and the upper bifurcated ends of the casing 14 keep the casing 14 from being displaced off the head, but by pulling down or inward upon the casing 14, against the action of spring 25, the casing can be tilted out of the large opening 13 and removed entirely from the head 5, at the will of the operator. Normally, the extreme upper ends of the casing 14 extend into side-sockets 28 (Fig. 1).

From the foregoing description, it will be understood that the head 5 can be readily adjusted at an angle to the shank 1, and that the auxiliary jaw 15 can be adjusted on the head with respect to the primary jaw 12, for accommodating different size nuts or bolt-heads.

While I have described the preferred em-

bodiment of my invention, and have illustrated the same in the accompanying drawings, certain minor changes or alterations may appear to one skilled in the art to which this invention relates, during the extensive manufacture of the same and I, therefore, reserve the right to make such alterations or changes as shall fairly fall within the scope of the appended claims.

10 What I claim is:

1. In a wrench of the class described, the combination with a shank, of a head provided with an integral jaw and with a central opening carried by said shank, a movable jaw provided with an integral neck carried by said head, said neck provided with teeth on one edge and extending across the central opening of the head, a casing provided with bifurcated ends straddling the neck, said casing provided with depending flanges contiguous to the sides of the head, a spring on the head and pressing against the casing, and an adjusting screw journaled upon the casing and normally meshing with the teeth of the neck.
2. In a wrench of the class described, the combination with a shank, of a head carried by the shank, said head provided with a large central opening and with an integral

jaw, a neck extending across the central opening and entirely through the head, said neck provided with an integral jaw at one end and with a groove in its side, said head provided with a rib extending into the groove of the neck, said neck provided with teeth in its lower edge, said head provided with side-sockets opening upon the central opening, a bodily movable casing in said central opening, said casing comprising a bottom having depending flanges at opposite edges, said flanges resting against the outer sides of the head, ends integral with the bottom of the casing and provided with bifurcations in their upper ends, the upper ends of the ends of the casing extending into said side-sockets of the head, a screw journaled at its ends in the ends of the casing and normally meshing with the teeth on the neck, said head provided with a spring-receiving socket, and a coil spring resting at one end in said spring-receiving socket and positioned under and pressing against the bottom of the casing, substantially as shown and described.

In testimony whereof I hereunto affix my signature.

JOHN WM. DAVIES.
